CLAIM

The ornamental design for a connector device for expanded cell confinement web, as shown and described.

DESCRIPTION

FIG. 1 is an upper perspective view of a connector device, according to the new design;

FIG. 2 is a lower perspective view thereof;

FIG. 3 is a front view thereof;

FIG. 4 is a rear view thereof;

FIG. 5 is right side view thereof;

FIG. 6 is left side view thereof;

FIG. 7 is top plan view thereof; and,

FIG. 8 is bottom plan view thereof.

The dash-dash broken lines are included for the purpose of illustrating portions of the connector device for expanded cell confinement web and form no part of the claimed design. The dot-dash broken lines define the bounds of the claimed design and form no part thereof.
